UNITED STATES PATENT OFFICE.

ELLIS J. G. PHILLIPS, OF AURORA, ILLINOIS, ASSIGNOR TO RICHARDS-WILCOX MANUFACTURING COMPANY, OF AURORA, ILLINOIS, A CORPORATION OF ILLINOIS.

TROLLEY APPARATUS.

Application filed February 7, 1925. Serial No. 7,614.

My invention relates to apparatus for transporting articles from one point to another, particularly in factories, warehouses, etc., by the use of trolleys running on tracks, 5 and has to do especially with trolley systems designed for use in situations where the articles handled are to be lowered from the track level at some stage of the course traveled by them, as, for example, where 10 they are to be painted by dipping them into a tank containing paint and then conveyed to some other point where they may dry while still carried by the trolley, a practice quite common in agricultural implement 15 and other factories. The object of my invention is to provide an improved trolley apparatus, of such character that a number of trolleys, each carrying its load, may be conducted in succession to the point where 20 their loads are to be lowered for treatment, and after the treatment has been administered, may be returned to the track level and conducted away thereon, without danger of accidentally damaging the articles that 25 are being handled. To this end it consists in providing a suitable track for supporting and conducting a plurality of trolleys, and providing such track with a section capable of being raised and lowered with one or 30 more of the trolleys upon it, and at the same time providing automatically controlled stop devices which will operate to prevent the trolleys from running off either end of the movable section of track or the 35 abutting ends of the stationary track sections. I accomplish this object as illustrated in the drawings and as hereinafter described. What I regard as new is set forth in the claims.

40 In the drawings, in which I have shown my invention applied to a track of the I-beam type designed for use with U-shaped trolleys having wheels running on the lower horizontal flanges of the I-beam at opposite 45 sides of the vertical web thereof,—

Fig. 1 is a side view of a portion of a trolley track that comprises a section movable vertically into or out of alinement with stationary track sections, the parts being 50 in their normal position;

Fig. 2 is a similar view showing the movable track section lowered with a trolley supported by it;

Fig. 3 is a plan view of the parts shown in 55 Fig. 1, some parts being broken away;

Fig. 4 is a detail, being a vertical cross-section on line 4-4 of Fig. 2;

Fig. 5 is an enlarged partial perspective view with the parts disposed as they are shown in Fig. 2;

Fig. 6 is a perspective view with the parts arranged as they are shown in Fig. 1; and

Fig. 7 is a bottom plan view of one end portion of the movable track section.

Referring to the drawings,—8, 9 indicate stationary track members that are securely mounted in any suitable way so that they form parts of a trolley track. Said members, in the form illustrated, are made of I-beams, the central web of which is indicated by 10, the two lower flanges on which the wheels of the trolley run by 11, 12, and the two upper flanges by 13, 14, as best shown in Fig. 5. The track members 8, 9 are alined, and as best shown in Fig. 2, they are spaced apart, their adjacent ends being inclined so that they diverge downwardly, as shown at 15, 16 in said figure. At their upper sides they are securely connected together by a beam 17, preferably of wood, 19 the end portions of which rest on plates 18, 19 and 20, 21, the plates 18, 19 being interposed between one end of the beam 17 and the track member 8, and the plates 20, 21 being similarly disposed between the other end of the beam 17 and the track member 9. The beam 17 is secured to the track member and to said plates by bolts 22, 23, or in any other suitable way. By this construction said beam bridges the gap between 90 the track members 8, 9, and is supported a short distance above the upper surfaces of said track members, the purpose of which arrangement will be hereinafter pointed out.

Arranged to fit snugly between the track members 8, 9, and to register therewith, is a vertically movable track section 24 which is also of I-beam construction. The ends of said track section 24 are inclined, as shown at 25, 26, to match the beveled ends of the 100 track members 8, 9, by which arrangement when the movable track section is raised to its normal position it will fit closely between the track members 8, 9 and cannot be lifted beyond such position, but will be free at all 105 times to be lowered out of engagement with the stationary track members. At its upper side the track section 24 is provided with a horizontal plate 27 which is fixedly secured thereto and projects laterally beyond each 110

of the upper flanges thereof. Also at one end said plate is provided with a portion 28 that extends longitudinally beyond the upper flange at one side of said track section, and at the other end it is provided with a similar projecting portion 29 that extends longitudinally beyond the upper flange at the opposite side thereof. This arrangement is best shown at the lower portion of Fig. 5. The extensions 28, 29 function as arms to hold up stops that protect the end portions of the stationary track members 8, 9, and also to move them out of operative position, as will be hereinafter described.

As will be understood from the foregoing, the track section 24 is intended to operate either as a continuation of the stationary track members 8, 9, or as a vertically movable support that may be lowered from its normal position to permit the load sustained thereby to be dipped in a paint bath, or to be lowered for any other desired purpose, as, for example, to deposit it on a truck or on the floor. To this end the track section 24 is sustained by cables 30, 31 connected to it adjacent to its ends, as illustrated in Fig. 2, and extending upward through suitable passages 32, 33 in the beam 17 to hoisting mechanism of any appropriate kind. In practice a single cable can well be used, a loop of the cable being connected with the track section 24 by clips 34, 35, 36, as shown in Fig. 2, and the end portions of said cable being connected with the hoisting devices. By this construction the track section 24 is held level while being raised or lowered, and the guide passages 32, 33 serve to prevent excessive lateral or endwise swinging thereof. By inclining the ends of the track sections 8, 9 and 24 as described, when the track section 24 is hauled up to its normal position, should it have swung endwise from its proper position in either direction, it will be guided to such position by the coacting inclined surfaces 15, 25 and 16, 26. For guiding the track section 24 laterally into its proper position when it is being raised, the beam 17 is provided with one or more, preferably two, guides 37, 38 in the form of inverted U-shaped plates having outwardly inclined lower ends 39, as illustrated in Figs. 5 and 6. The vertical portions 40 of these guides are spaced apart a distance approximately equal to the width of the plate 27 carried by the movable track section 24, as shown in Fig. 6, and consequently said guides prevent lateral movement of said track section when it is in its raised position. Also the inclined lower ends 39 of said guides, through their engagement with the side margins of the plate 27, should it be out of its proper position while being hoisted, direct said track section as it rises into alignment with the stationary track sections 8, 9. By this means the proper alignment of

the movable track section 24 with the other track sections is assured.

To protect the end portions of the stationary track sections 8, 9 at opposite sides of the gap when the movable track section 24 is lowered, and prevent trolleys carried by said stationary track sections from running off at the gap, swinging stops 41, 42 are provided, one of said stops being associated with each of said track sections 8, 9, as shown in Figs. 2 and 3. These stops are alike, and are in the form of plates pivoted at opposite sides and at opposite ends of the beam 17 by means of bolts 43, 44 in such manner that they are adapted to swing vertically in planes parallel with the track sections 8, 9. When said stops are in their operative position they extend down in position to intercept a trolley running on the stationary track section with which they are associated, as illustrated in Figs. 2 and 5, but normally they are held up out of operative position so that they do not interfere with the passage of the trolleys along the track, as illustrated in Figs. 1 and 6. The stop plates 41, 42 are best made of the shape shown in the drawings, being provided with a straight-edge 45 that is approximately vertical when the stop plate is in its operative position, a straight-edge 46 that is substantially parallel with the edge 45 and lies at the opposite margin of the plate and somewhat closer to its pivot, and an inclined edge 47 disposed between the edges 45 and 46. The edge 45 is that which is adapted to intercept a trolley on the adjacent stationary track section and prevent it from moving toward the gap. The edge 46 is adapted to cooperate with one or the other of two laterally projecting lugs 48, 49 carried respectively by the plates 19, 21, as shown in Figs. 2 and 3, so that the lower ends of the stop plates 41, 42 are prevented from swinging toward the gap between the stationary track sections after they assume their operative position. At the right in Fig. 2 the stop plate 41 is shown in its operative position with its edge 46 in engagement with the lug 48. The inclined edge 47 is intended to cooperate with the extension 28 or 29, as the case may be, when the movable track section 24 is being hoisted to its normal position to raise the stop plates 41, 42 to their inoperative position. Referring to Fig. 2, it will be seen that the extension 28 underlies the inclined margin 47 of the stop plate 41 when the latter is in its operative position and the movable track section 24 is lowered. It will be evident, therefore, that when said track section is raised high enough, the extension 28 will strike the inclined edge 47, thereby causing the stop plate 41 to swing counter-clockwise as the track section 24 rises, until finally by the time said track section reaches its normal

position in alinement with the stationary track sections 8, 9 the stop plate 41 will have been raised to the position shown in Fig. 1, leaving the track free for the passage of 5 trolleys. At that time the edge 46 of the stop plate will rest on the extension 28 and be supported by it. A similar operation takes place at the other end of the movable track section. When the movable track section 24 is lowered, the stop plates 41, 42 are permitted to drop to their operative position, when their edges abut against the lugs 48, 49, as above described, thereby preventing them from swinging towards the gap 15 between the stationary track sections after they have reached their operative position. It will be seen from the foregoing description that the position of the stop plates 41, 42 is automatically controlled by the movement of the movable track section, and that the stationary track sections at opposite sides of the gap are always protected so that trolleys on either of said track sections cannot run off accidentally when the intermediate or movable track section is out of its operative position. The shape of the stop plates 41, 42 may be varied considerably, as while I prefer to make them of the shape shown and described, they may be of any 30 other suitable shape calculated to permit them to function as described.

It is also desirable that means be provided for preventing the trolley or trolleys carried by the movable track section 24 from running off such section when it is out of its operative position, and to this end said track section is provided with stops 50, 51 at its opposite ends associated with its lower flanges 11, 12. These stops extend longitudinally of the track section 24 and are pivoted between their ends on transverse pivots 52 secured to the track section 24 in any suitable way, as by bearing plates 53, the arrangement being such that said stops 45 may swing vertically to a limited extent. The pivots 52 are located near the lower ends of the track section 24, and the stops 50, 51 are provided with V-shaped portions 54 that extend beyond the ends of said track section, as illustrated in Figs. 2 and 5. The opposite ends 55 of said stops are somewhat longer and heavier than the ends 54, so that they overbalance the ends 54 and therefore tend to throw the latter ends up somewhat above the level of the lower surface of the track section 24. Excessive downward movement of the ends 55 is prevented by the engagement of the ends 54 with the end portions of the track section 24, as illustrated in Fig. 2, the upper surfaces of the ends 54 being preferably notched slightly to receive the end margins of the track section 24, as indicated at 56 in Fig. 2. Obviously when the track section 24 is raised 60 to its normal position, the projecting ends

54 of the stops 51, 52 will strike the lower margins of the stationary track sections 8, 9 and be moved downward, thereby raising the inner or opposite ends of said stops to a position parallel with the lower surface 70 of the track section 24, as illustrated in Fig. 1. When, however, the track section 24 is lowered, the weight of the inner ends of said stops will cause them to swing downward to the position shown in Figs. 2 and 5. 75 In Fig. 2 I have illustrated a trolley 57 in position on the track section 24, and it will be obvious that the inner ends 55 of the stops 50, 51 are adapted to intercept the trolley should it be about to run off either 80 end of said track section, thereby preventing it from doing so. Preferably the flanges 11, 12 of the track section 24 are recessed, as shown at 58 in Fig. 5, to center the trolley on said track section, as it is 85 obviously desirable to keep the weight as near the longitudinal center of the movable track section as possible while it is being raised or lowered.

The beam 17 is spaced from the track sections by the plates 18, 20 to accommodate the plate 27 and the transverse portions of the guides 37, 38, the intermediate portion of said beam at the underside thereof being preferably cut away, as shown in Figs. 1 90 and 2, to provide more room for said guides and also for the horizontal portion of the hoisting cable 30.

What I claim as my invention and desire to secure by Letters Patent, is— 100

1. A trolley apparatus comprising two stationary track sections having end portions spaced apart, an overhead beam connecting said stationary track sections, a vertically movable track section adapted to fit between and connect said stationary track sections, lateral guides supported by said beam and disposed at opposite sides of said track sections for directing said movable track section into operative relation with 105 said stationary track sections, safety stops associated with the end portions of said stationary track sections and movable into position to block the same, and means for moving said stops out of operative position when said movable track section is moved into operative relation with said stationary track sections. 110

2. A trolley apparatus comprising two stationary track sections having end portions spaced apart, a vertically movable track section adapted to fit between and connect said stationary track sections, safety stops associated with the end portions of said stationary track sections and movable into 120 position to block the same, vertically swinging safety stops associated with the end portions of said movable track section and having members adapted to engage said stationary track sections when the movable track 125

130

- section is moved into operative relation therewith, and to be actuated thereby to move the latter stops out of operative position, and means carried by said movable track section for moving said first-mentioned stops out of operative relation to said stationary track sections when the movable track section is moved into operative relation with said stationary track sections.
13. 3. A trolley apparatus comprising two stationary I-beam track sections having end portions spaced apart, a vertically movable I-beam track section adapted to fit between and connect said stationary track sections,
14. vertically swinging safety stops associated with the end portions of said stationary track sections and adapted to swing by gravity into position to block the same, vertically swinging safety stops at the end portions of said movable track section and arranged to drop by gravity below the lower margin thereof to block the same, the latter stops having members adapted to engage the lower marginal portions of said stationary track sections, and to be actuated thereby when said movable track section is moved into operative relation therewith to move the latter stops out of operative position, and means carried by said movable track section
15. for moving said first-mentioned stops out of operative position when said movable track section is moved into operative relation with said stationary track section.
4. A trolley apparatus comprising two stationary track sections having end portions spaced apart, a beam connecting said track sections, a vertically movable track section adapted to fit between and connect said stationary track sections, a cable extending
16. through vertical passages in said beam and connected with the end portions of said movable track section, and lateral guides for said movable track section carried by said beam.
5. A trolley apparatus comprising two stationary track sections having end portions spaced apart, an overhead beam connecting said stationary track sections, a vertically movable track section adapted to fit between and connect said stationary track sections, means for raising and lowering said movable track sections, and guide means supported by said beam for directing said movable track section into operative relation with said stationary track sections.
55. 6. A trolley apparatus comprising two stationary track sections having end portions spaced apart, an overhead beam connecting said stationary track sections, a vertically movable track section adapted to fit
60. between and connect said stationary track sections, cable means for raising and lowering said movable track section, and guide
- means associated with said overhead beam for guiding said cable means.
7. A trolley apparatus comprising two stationary track sections having end portions spaced apart, a beam connecting said track sections, a vertically movable track section adapted to fit between and connect said stationary track sections, and a safety stop associated with said stationary track section and actuated to move into and out of operative position by movement of said movable track section out of or into operative relation with said stationary track sections.
8. A trolley apparatus comprising two stationary track sections having end portions spaced apart, a beam connecting said track sections, a vertically movable track section adapted to fit between and connect said stationary track sections, and a safety stop associated with said movable track section and actuated to move into or out of operative position by movement of said movable track section out of or into operative relation to said stationary track sections.
9. A trolley apparatus comprising a stationary track section, a track section movable vertically into and out of alignment therewith, and a safety stop movably supported adjacent the lower edge of said movable track section and comprising a stop portion adapted to project down below the bottom of said movable track section for blocking movement of the trolley.
10. A trolley apparatus comprising a stationary track member of I beam section, a similar vertically movable track member adapted to align therewith, and a safety stop pivotally supported on said movable track member and comprising a stop portion adapted to project below the bottom of said movable track member, said safety stop being movable into and out of operative position by the movement of said movable track member out of or into operative relation to said stationary track member.
11. A trolley apparatus comprising a stationary track member of I beam section, a similar vertically movable track member adapted to align therewith, and safety stops pivotally supported at each end of said movable track member, each of said safety stops comprising a stop portion adapted to move into the path of a trolley on said movable track member, said safety stops being movable into and out of operative position by the movement of said movable track member out of or into operative relation to said stationary track member.

ELLIS J. G. PHILLIPS.
